UNITED STATES PATENT OFFICE.

AUGUST R. SCHOENKY, OF SOMERVILLE, MASSACHUSETTS, ASSIGNOR TO THE REECE SHOE MACHINE COMPANY, OF BOSTON, MASSACHUSETTS, A CORPORATION OF MAINE.

SEWING-MACHINE.

1,137,356.

Specification of Letters Patent. Patented Apr. 27, 1915.

Original application filed September 25, 1912, Serial No. 722,300. Divided and this application filed January 7, 1913. Serial No. 740,640.

To all whom it may concern:

- Be it known that I, AUGUST R. SCHOENKY, a citizen of the United States, residing at Somerville, in the county of Middlesex and State of Massachusetts, have invented certain new and useful Improvements in Sewing-Machines, of which the following is a specification, reference being had therein to the accompanying drawing.
- 10 My invention relates to sewing machines and more particularly to that class of machines employing a rotary shuttle carrying a bobbin, in which is a supply of thread adapted to be interlocked with a second thread in the operation of the sewing machine.
- Specifically, I have applied the present improvement to a lock stitch sewing machine of the type employed in the manufacture of shoes by the welt system, wherein the out sole and the welt are sewed together. The substantial details of such a sole sewing machine are fully disclosed in my prior application, Serial No. 722,300, filed September 25, 1912, of which the present application is a division, and reference may be made to said prior application for details not illustrated herein.
- It is an object hereof to provide a novel and improved bobbin retainer and operating mechanism, whereby the shuttle box may be opened and shut for the removal and replacement of bobbins.
- 35 Other objects and advantages pertaining to the present invention will appear in the hereinafter following description or will be apparent to those skilled in the art.
- To the attainment of such objects and advantages, the present invention consists in the novel combinations, arrangements, devices, and parts set forth, described and illustrated in the following description and accompanying drawings.
- 45 I will first describe one form of machine embodying my improvements and will thereafter point out the novel features in the claims.
- In the accompanying drawings forming a part hereof, Figure 1 is a front view, partly broken away, showing the shuttle case, the shuttle, the bobbin retainer, and the re-
- 55 tainer operating mechanism. Fig. 2 is a top view partly in section upon the plane 15—15 of Fig. 1.
- Similar lines and references designate corresponding parts in the several figures of the drawing.
- Without attempting any description of the general construction of the machine, or details not involved in the present improvement, I call attention that those details may be as in my aforesaid prior application, or of any other description. The upper thread from the bobbin hereof will be understood to be interlocked with an under thread properly manipulated by any suitable mechanism.
- 60 The shuttle case 10 will as usual be employed and this may be of the ordinary form as indicated, having a somewhat enlarged casting or body, to the front of which is secured the shuttle retainer 11 in the usual form of a ring, it serving to confine within the case the shuttle 12 which encompasses the bobbin 13, the latter retained in place by the device or retainer 14. The shuttle may be driven in a rotary manner by any suitable mechanism such as the usual driver shaft having at its front end the driver part or lug 65.
- 65 The bobbin 13 hereof is of a form which is not new herein, having a forwardly extending projection or ridge extending upwardly and downwardly and engaging in a corresponding recess or valley in the retainer 14, so that the bobbin is retained, but, at the same time, the thread is permitted to pass between the bobbin and retainer.
- 70 I provide herein means for locking the retainer when closed and means, as a spring, for throwing it open when unlocked. There is also a manual part movable at will for causing the unlocking and thereby the throwing open of the retainer, the parts being so constructed or designed that the locking device is held inoperative when the retainer is open, so that the latter may at any time be moved by simply pushing toward closed position for re-locking it. One hand therefore serves for releasing and opening when desired, and one hand may close and lock the retainer when desired. Specific mechanism for accomplishing these ends
- 75

- 85
- 90
- 95
- 100

may be as follows: The retainer 14 is shown at the end of a carrying arm 142, which is pivoted to a stud or bolt 143, (see Figs. 1 and 2). A coil spring 144 is so secured at 5 its inner and outer ends respectively to the bolt 143 and the arm 142 as to tend to throw the latter wide open. When the retainer 14 is closed upon the bobbin, it is positively held there by the extension 145 of the arm 10 142, said extension having a tapered aperture 146, adapted to be engaged by a tapered pin 147, vertically mounted in part of the shuttle case 10. A spring 148 tends to throw downwardly the pin 147 so as to 15 wedge it into the recess 146, for securely and rigidly locking the bobbin retainer in closed position.

To unlock the bobbin retainer, and at the same time to open it, I have provided the 20 coil spring 144, before referred to, and also an opening part or rod 149, having an accessible knob or handle shown at the top thereof. The rod 149 has lateral teeth 150 at one side, engaging a pinion 151 mounted 25 in the shuttle case, such pinion engaging teeth 152 on the locking bolt 147. With such mechanism, if the operator depresses the rod 149, the bolt 147 is lifted and the spring 144 causes the bobbin retainer to 30 swing completely open. To determine the limit of opening, a stop 153 may be located substantially as shown, which will contact the body of the shuttle case, as indicated in the dotted line position of Fig. 2.

35 It will be noticed that the carrying arm 142 has a flat upper surface of arc shape or form, so that during the swinging from the full line to the dotted line position the bolt 147 is upheld or prevented from descending 40 under the influence of spring 148. The result of this arrangement is that after the operator has opened the retainer by a mere pressure of the rod 149, he is easily enabled at will to close the retainer without operation 45 of the rod 149, but merely by pushing the retainer to swing it shut. The bolt 147 slides around the upper surface of the arm 142, until it drops into the aperture 146, to positively lock the retainer in closed position. 50

I have thus described a mechanism which attains the advantages and objects hereinbefore recited. Since it is manifest that various parts, features and combinations 55 may be modified in form or operation without departing from the principles of the invention, I do not wish to be limited to any specific features, arrangements, parts or other details, excepting in so far as the same 60 are referred to in the appended claims.

What I claim and desire to secure by Letters Patent is:

1. In a sewing machine the combination 65 of a shuttle adapted to contain a bobbin, a movable bobbin retainer adapted when in

closed position to retain a bobbin in said shuttle, an apertured plate movable with said retainer, a locking bolt adapted to engage the aperture in said plate to positively lock the retainer in closed position, and 70 means, including a single controller or handle, operable at will for disengaging said bolt and plate and permitting the moving of the retainer into open position, and a means other than said controller for moving 75 open the retainer; said bolt and aperture being so relatively formed as to readily engage upon closing the retainer and so constructed not only to lock the retainer against opening movement but to afford a stop to 80 the closing movement.

2. In a sewing machine the combination of a shuttle adapted to contain a bobbin, a horizontally swinging bobbin retainer adapted when in closed position to retain a 85 bobbin in said shuttle, an apertured plate horizontally movable with said retainer, a self-descending locking bolt above said plate adapted to engage from above the aperture in said plate to positively lock the retainer in closed position, a single controlling handle having connections for disengaging said bolt and plate such that the bolt is moved upward by a suitably convenient motion of the handle, and means acting automatically upon the operation of the handle for swinging the retainer open. 90

3. In a sewing machine the combination of a shuttle adapted to contain a bobbin, a horizontally swinging bobbin retainer 100 adapted when in closed position to retain a bobbin in said shuttle, an apertured plate horizontally and rigidly movable with said retainer, a self-descending locking bolt located wholly above said plate adapted to engage from above the aperture in said plate to positively lock the retainer in closed position, a single controlling handle above said plate, and having connections for disengaging said bolt and plate such that the bolt is 105 moved upward by a suitably convenient motion of the handle, and means also located above said plate, acting automatically upon the operation of the handle for swinging the retainer open. 110

4. In a sewing machine the combination of a shuttle adapted to contain a bobbin, a horizontally swinging bobbin retainer adapted when in closed position to retain a bobbin in said shuttle, an apertured plate 120 horizontally and rigidly movable with said retainer, a self-descending locking bolt located wholly above said plate adapted to engage from above the aperture in said plate to positively lock the retainer in closed position, a single controlling handle above said plate, and having connections for disengaging said bolt and plate such that the bolt is 125 moved upward by a suitably convenient motion of the handle, a flat bottomed fixed 130

frame part directly above said plate, and against which the plate swings in direct face contact, and in which the pivot of swinging is located, the plate and frame part constructed with a central recess, and a spiral spring within said recess adapted to swing the retainer open when unlocked.

In testimony whereof I affix my signature in presence of two witnesses.

AUGUST R. SCHOENKY.
